DEVICE FOR RECLAIMING THE TOBACCO FROM DEFECTIVE CIGARETTES

Horst Kochalski, Hamburg-Bergedorf, and Kurt Körber, Hamburg-Bahrenfeld, Germany, assignors to Kurt Körber & Co. Kommandit-Gesellschaft, Hamburg-Bergedorf, Germany, a German firm

Application August 27, 1949, Serial No. 112,638

Claims priority, application Germany July 12, 1949

2 Claims. (Cl. 131—96)

This invention relates to a device for alining stick-like articles and more particularly for alining cigarettes which have been rejected at inspection after their manufacture, and the hull of which has to be cut to reclaim the tobacco. Devices have been built to slit the paper hulls of the cigarettes and subject hulls and tobacco to a screening operation in rotating screening drums or the like, to separate the paper from the tobacco. For the purpose of slitting the hull lengthwise, the cigarettes have to be alined in relation to the slitting knife. Known devices for alining cigarettes introduced at random generally have orifices, slides, belts, and other mechanical means to adjust the cigarettes and feed them properly to the cutting knife. These devices have the disadvantage of being complicated, having channels which easily clog, and require continuous supervision. Besides, their capacity is small and they cause undesirable cutting of the tobacco because of improper alinement.

An object of this invention is to provide a simple device which eliminates the drawbacks mentioned above. This device makes use of centrifugal force, rather than mechanical contrivances for the alinement of the sticks. Cigarettes and other stick-like articles, entered into the device according to the invention are subjected to centrifugal forces which carry the cigarettes against a circular collar where they are alined into an annular string. At a convenient point, the circular collar is interrupted to form a tangential aperture. Centrifugal force in combination with a force tending to move the cigarettes circumferentially along the collar serves to extrude the cigarettes through this aperture, all properly alined. Additional objects will become apparent from the following specification and the drawing which shows diagrammatically a preferred device according to the invention. In the drawing:

Fig. 1 is a partial central sectional view of the device according to the invention;

Fig. 2 is a top view of the device shown in Fig. 1, the top portion of the housing being omitted;

Fig. 3 is a sectional view of a modified portion of the device according to Figs. 1 and 2.

The same numerals designate the same parts in all figures.

Referring to the drawing, a disc 1 rotates at high speed inside a stationary collar 2, which, in the example shown in the drawing, is formed by the lower rim of a dome-shaped housing having an opening 3. Into this opening rejected cigarettes are thrown at random landing on the top face of the disc 1 which rotates at high speed. Centrifugal forces acting on the cigarettes as soon as they touch the disc urge the cigarettes against the inner face of collar 2 where they form a string 4 on the rim of disc 1 and revolve with the disc. It is preferred to knurl or otherwise roughen the surface of the rotating disc 1 at the center and at the rim to positively transmit the revolving motion to the cigarettes. The inner surface of collar 2, however, is preferably very smooth so that the cigarettes will slide along easily. The three arrows at the lower portion of Fig. 2 illustrate the paths which the cigarettes will take within the casing 2. The path of the cigarettes relatively to the disc 1 is in opposite direction to the arrows.

An aperture 5 is provided in the collar 2 substantially in tangential relation to the rim of the rotating disc 1, the cigarettes entering this aperture under the influence of the rotation of the disc and of centrifugal force. Within the aperture a circular cutting knife 6 is suitably arranged to slit the hulls of the cigarettes entering the aperture.

2

A wall portion 6' may be provided to guide the cigarettes. The slit cigarettes hit a baffleplate 7 behind the aperture, as shown in Fig. 2, and drop into a basket or a screening drum not shown in the drawing for segregating the tobacco from the paper in any known manner. To prevent too many cigarettes from accumulating at the entrance of the aperture 5 and possibly clog the aperture a deflector 8 is suitably interposed which preferably rotates as shown by the curved arrow at the left portion of Fig. 2, 5 in the opposite direction as the disc 1. This deflector diverts cigarettes not alined in the string 4, throwing them back on the disc 1 until they find a place within the string. 10 It will be understood that other means for severing the cigarette hull may be used instead of the knife 6. It is 15 possible to sever the hull by squeezing or pressing the cigarettes when a suitable moistening device, for example a spray nozzle 9, is interposed within the opening 3 as seen in Fig. 3 and the cigarettes are sufficiently moistened so that a squeezing roller 6c, replacing knife 6, can 20 easily sever the hull.

Having thus described preferred embodiments of our invention, we do not wish to be limited thereto, but desire the appended claims to be construed as broadly as permissible in view of the prior art.

25 What we claim is:

1. A device for reclaiming the tobacco from defective cigarettes comprising a substantially horizontal rotating disc-like means onto which the defective cigarettes are adapted to be dropped at random and to be subjected to 30 a centrifugal force, a stationary substantially vertical circular wall member disposed at the periphery of said disc-like means for stopping outwardly directed radial movement of the cigarettes and together with the rotating disc converting it to a sliding movement along and substantially parallel to said wall member, said wall member having an aperture affording discharge of the cigarettes 35 in sequence, a relatively stationary severing means disposed adjacent to said aperture for severing the wrappers of the cigarettes as they move through said aperture, 40 and a deflecting means mounted on said wall member adapted to engage cigarettes which are not in a suitable position for entering said aperture, and to deflect them towards the center of the disc-like means for resubjecting the deflected cigarettes to the centrifugal force.
- 45 2. A device for reclaiming the tobacco from defective cigarettes comprising a substantially horizontal rotating disc, a stationary cover for said disc having an opening through which the defective cigarettes are adapted to be dropped at random onto said disc and to be subjected to 50 a centrifugal force, said cover having a substantially vertical circular wall portion disposed at the periphery of said disc for stopping the outwardly directed radial movement of the cigarettes and together with the rotating disc converting it to a sliding movement along and substantially parallel to said wall portion, said wall portion having an aperture affording discharge therefrom and from 55 said disc of the cigarettes sliding along said wall portion, means for removing misaligned cigarettes from the wall portion adjacent to said aperture, moistening means disposed in said opening for moistening the cigarettes, and a squeezing roller disposed adjacent to said aperture and engaging the cigarettes moving therat for severing their 60 wrappers by the application of pressure.
